PILE FABRIC AND METHOD OF MAKING
SAME

Howard L. Shuttleworth, Amsterdam, N. Y., assignor to Mohawk Carpet Mills, Inc., Amsterdam, N. Y., a corporation of New York

Application February 23, 1939, Serial No. 257,904

15 Claims. (Cl. 139—406)

This invention relates to woven pile fabrics, such as rugs and carpets, in which the pile is formed by the use of wires inserted in the shed during the weaving operation to produce pile loops. More particularly, the invention is concerned with a novel fabric of the type referred to in which an embossed or relief effect is obtained in the pile surface by means of loops of different heights, and a new method of producing such a fabric.

In looms of the type in which pile wires are used, the wires are inserted in the shed between the warps used in forming the body of the fabric and the pile warps, and are beaten up by the lay and bound in place by loops of the pile warp yarns. In the weaving operation, each wire remains in the fabric until a number of others have been inserted behind it, whereupon, it is withdrawn from the fabric, advanced to the head of the series, and again inserted in the open shed. In the production of such fabrics, the pile surface may be given a design or pattern by the use of pile warp yarns of different colors which are raised at selected points to form loops by a jacquard mechanism. Also, the loops may be left in their original condition upon withdrawal of the wires or they may be cut by knife edges on the wires during withdrawal of the latter.

Heretofore, fabrics embodying relief effects in the pile surface have been produced on looms of the construction referred to by the use of pile wires of different heights. Thus, the pile yarns used to produce the pile loops in the ground area may be formed by wires of one height and the loops in the figures or in parts of the figures of the design may be formed by means of wires of a different height. Fabrics thus produced are objectionable, however, because in a single transverse row of loops, the loops must be all of the same height, since they are all formed on the same wire. As it is impossible, in such a loom, to obtain pile loops of different heights in the same transverse row, these fabrics contain spaces devoid of tufts in those rows which pass through areas where the pattern requires tufts of different heights. The presence of such spaces in the pile surface detracts from the appearance of the fabrics and has reduced the sales possibilities thereof.

Attempts have been made to overcome the difficulty referred to and to produce pile loops of different heights in the same row by employing differentially twisted yarns for the pile. The pile of a fabric so produced contains yarns of different twist in single rows and after the fabric is

finished, the pile surface is treated to modify the twist in certain of the pile loops. Such treatment causes some loops either to sink below or to rise above the loops not affected by the treatment and the resulting pile surface is made up of loops of different heights. While this method permits the production of a fabric having pile loops of different heights in the same row, it does not provide positive control of the height of the loops, since all the loops will not respond in like manner to the treatment by which the twist is modified.

The present invention is, accordingly, directed to the provision of a new pile fabric having a pile surface embodying relief effects, which is free of the objections to which the prior fabrics are subject, and a novel method by which the fabric of the invention may be produced in a practical and economical manner. The new fabric is superior to prior fabrics in that each transverse row of loops contains its full complement and these loops may be of different heights. Also, the formation of the loops throughout the fabric is so controlled that loops of different heights are accurately produced at selected points, as may be desired. The method of the invention may be practised on a standard Wilton type of loom modified by the use of wires of a novel form and by employing a pattern of appropriate type, the wires being utilized in conjunction with the jacquard mechanism to produce the desired effects in the finished goods.

The novel wires referred to are of uniform height throughout the portion of their length on which the pile loops are formed, but that end of each wire which is last withdrawn from the loops is of increased height. As the pile warp yarns are laid over such a wire and the latter is bound in place by the yarns, a row of loops of uniform height is formed, and on withdrawal of this wire, each loop is enlarged in order to pass over the high end of the wire. If such a loop is formed of a yarn which has previously been embedded in the fabric, the additional length of yarn required for the increase in height of the loop is obtained by the stretch of the embedded portion of the yarn. If the loop to be enlarged is the second in a longitudinal series of loops made of the same yarn, the additional length for increasing the height of the loop is obtained by reduction in the height of the preceding loop. Thus, in a longitudinal series of loops of the same yarn, the withdrawal of each wire increases the height of the loop formed over it and in doing so results in either stretching the embedded portions of the

yarn or decreasing the height of the preceding loop of the yarn. When the wire in the last loop in such a series, immediately preceding an embedded portion of the yarn, has been withdrawn, 5 leaving the loop with an increased height, this last loop retains that height, and, as consequence, throughout the fabric, each pile area of a single color or type of yarn is outlined along the margin last formed by loops of greater height than those 10 within the area. By employing two or more pile forming yarns of different colors or types and providing loops of increased height in the fabric just before a change in the yarns, the embossed or relief effect above referred to is produced.

15 For a better understanding of the invention reference may be had to the accompanying drawing, in which:

Fig. 1 is an enlarged longitudinal view in section showing one form of the new fabric in the process of manufacture and illustrating the manner in which the pile loops bind the wires in the fabric before the wires are withdrawn;

Fig. 2 is a side view of the end portion of a pile wire used in making the new fabric;

25 Figs. 3 and 4 are enlarged longitudinal views in section of part of the fabric shown in Fig. 1 illustrating the formation of the high and low pile loops on withdrawal of the pile wires;

Fig. 5 is a view similar to Fig. 1 illustrating 30 the fabric after the withdrawal of the wires and showing the relation of the long and short pile loops which form the high and low pile areas in the pile surface to produce the embossed or relief effect of the invention, and

35 Fig. 6 is a perspective view of a piece of finished fabric made in accordance with the invention.

The backing of the fabric may be of any suitable construction, but in the form illustrated is 40 of the two-shot Wilton type including stuffer warps 10 and two series of weft threads 11 and 12 lying, respectively, above and below the stuffer warps and bound in place by two sets of binder warps 13 and 14. Pile forming yarns 15, 16 and 45 17 are extended along the fabric in the body thereof between the stuffer warps and the upper series of weft threads 12, until they are selected by the jacquard mechanism (not shown) and raised over pile wires 18 to 32, inclusive, to form 50 the pile loops. The yarns 15, 16 and 17 are preferably of contrasting appearance, as for example, of different colors, depending on the pattern which is desired. It will be understood that the 55 backing of the fabric may be woven in any suitable manner other than that shown to furnish a proper support for the pile loops. For example, the backing may consist of a single set of binder warps or may have three sets of weft threads for each pile loop. Also, the number of pile forming 60 warps may be varied in accordance with the desired pattern.

The weaving of the fabric may be conveniently 65 performed in the standard Wilton type of loom employing a jacquard for controlling the pile warps but modified by the use of pile wires which are of increased height at one end, as shown in Fig. 2. The wire there shown includes the usual body portion *a*, which may be of any desired 70 height, and an end portion *b* which is somewhat higher than the body portion and is generally spoon-shaped. In the drawing, I have shown a series of fifteen of these wires bound in the fabric in the weaving operation by the pile forming 75 warps 15, 16 and 17 which are looped over the

wires. It will be apparent, however, that the number of wires in the series may be varied.

In the weaving operation, the jacquard raises one of the yarns, such as the yarn 15, for example, from the body of the fabric under the weft threads 12, and the first wire 18 is inserted in the shed formed by the raising of this yarn, after which the yarn 15 is looped over the wire 18 by the lowering of the yarn strands to pass under the next upper weft thread. In a like manner, 10 according to the pattern desired, wires 19, 20 and 21 are inserted in the sheds formed by the raising of yarn 15, and when the yarn is looped over wire 21 it is returned to the body of the fabric and extended along within the body for some distance. After the yarn 15 is passed over wire 21 and back into the fabric, the jacquard raises another of the yarns, the yarn 16, for example, and passes it successively over the wires 22 and 23, after which it is returned to the body of the fabric. Then, according to the pattern, the jacquard selects another yarn, such as the yarn 15, which is successively looped over wires 24 to 27, inclusive, and passed back into the body of the fabric. The next selection by the jacquard causes yarn 16, for example, to be looped successively over wires 28 and 29, and in a like manner a different yarn, such as the yarn 17, is then looped over wires 30, 31 and 32. All of the wires in the series are now inserted in the fabric so that on each wire a transverse row of loops extends over the body portion *a*, the end portion *b* of the wire extending beyond the loops.

The cycle is now repeated by withdrawing the first inserted wire 18 and inserting it again in 35 the shed which is formed immediately after the insertion of the last wire 32 of the series, as shown in dotted lines in Fig. 1. Similarly, the wire 19 is withdrawn from the loops, and inserted in the shed which is formed immediately 40 after the insertion of wire 18 in its new position, etc.

In withdrawing the wire 18 from its initial position in the fabric, the loops on it are forced to pass along the wire over the end portion *b* 45 and in so doing are stretched from a height corresponding to the body portion *a* to a height corresponding to the end portion *b* of the wire. In this stretching of the loops, the yarn 15, in the longitudinal row of loops shown in Fig. 1, is 50 drawn from under the previously inserted weft thread 12, and sufficient yarn is thus obtained to form the loop 18c of a height substantially the same as the height of the end portion *b* of the wire. When the next wire 19 is withdrawn, 55 the loops thereon are caused to stretch in a similar manner from a height corresponding to the body portion *a* to a height corresponding to the end portion *b* of the wire, and in this stretching, the yarn strands are drawn from under the previously inserted weft thread with the result that the height of the loop 18c is reduced to a height 60 18', as shown in Fig. 4. At the same time, the enlarged loop 18d is formed which is substantially the same height as the previously formed 65 loop 18c. The wires are thus withdrawn successively and re-inserted, as described, but when a wire immediately preceding a yarn change is withdrawn, such as the wire 21, the loop of increased height which it leaves retains that height 70 because the yarn necessary to increase the height of the next loop 22' in the same longitudinal row is obtained, not from the loop 21' preceding it, but from the embedded portions of the new 75 yarn 16.

When all of the wires have been withdrawn, the longitudinal row of loops shown by way of example in Fig. 1 has the appearance illustrated in Fig. 5. As there shown, the loops 18', 19', and 20' are of the same height, while loop 21', which is the last loop formed prior to a yarn change, is higher than the loops 18' to 20' and corresponds substantially to the height of the end portion *b* of the previously withdrawn wire. Throughout the fabric, therefore, the last loop formed prior to a yarn change is a high loop, and the preceding loops from the same yarn strands are low loops. Thus, as shown in Fig. 5, there is a yarn change immediately following loops 21', 23', 27', 28', 32' and 19'', and accordingly the latter loops are higher than the others illustrated. It will be understood that the order of the yarn changes in the longitudinal rows of loops in the fabric may vary in different rows, depending on the desired pattern. Also, while the loops are shown as uncut after withdrawal of the wires, some or all of them may be cut, as, for example, by means of cutting edges on the wires which sever the yarns as the wires are withdrawn.

By the practice of the new method, the ground pile area of the fabric may be formed of loops of a relatively low height and the pattern area may be outlined at as many points as desired by loops of a greater height. While the design to be woven is preferably selected so that at least two loops are formed before each yarn change, thereby permitting the formation of a high loop by reducing the height of the preceding loop, it is possible to form a single high loop immediately following a yarn change. This may be accomplished by using a yarn having sufficient stretch or elasticity to allow the loop to expand and thus pass over the high end portion *b* of the pile wire when there are no immediately preceding loops of the same yarn from which to draw the extra material.

It will be apparent that with the new method it is possible to obtain any combination of high and low pile loops in a transverse row of the fabric, depending on the selection of the pile yarn by the jacquard. The novel fabric of the invention is produced with a pleasing embossed or relief effect and is superior to prior fabrics in that it does not have spaces devoid of tufts. Since the pile wires employed may be of the same height, the new fabric may be produced efficiently and at low cost and, in addition, with an accurate control of the height of the tuft loops. Any desired relationship in the heights of the low and high loops may be readily obtained by suitably proportioning the heights of the body portion *a* and the end portion *b* of the new pile wire.

60 I claim:

1. A pile fabric which comprises the combination of stuffer warps, weft shots lying above and below the stuffer warps, binder warps crossing the weft shots above and below and binding the weft shots in place, and a plurality of sets of pile warps held in place by portions lying between the upper and lower weft shots, other portions of the pile warps being raised between adjacent upper weft shots in accordance with a pattern to provide loops lying in rows extending transversely of the fabric, each row containing a full complement of loops, and the last loop in any longitudinal series of loops of a single pile warp yarn being higher than the other loops in said series.

2. A pile fabric which comprises the combination of stuffer warps, weft shots lying above

and below the stuffer warps, binder warps crossing the weft shots above and below and binding the weft shots in place, and a plurality of sets of pile warps of different colors held in place by portions lying between the upper and lower weft shots, other portions of the pile warps being raised between adjacent upper weft shots in accordance with a pattern to provide loops in pile areas of different colors, the loops along the end margins of the areas longitudinally of the fabric being of different height from those inward from said margins.

3. A pile fabric which comprises the combination of stuffer warps, weft shots lying above and below the stuffer warps, binder warps crossing the weft shots above and below and binding the weft shots in place, and a plurality of sets of pile warps of different colors held in place by portions lying between the upper and lower weft shots, other portions of the pile warps being raised between adjacent upper weft shots in accordance with a pattern to provide loops in pile areas of different colors, the loops along the margins of the areas being higher than those spaced from said margins.

4. A pile fabric which comprises the combination of stuffer warps, weft shots lying above and below the stuffer warps, binder warps crossing the weft shots above and below and binding the weft shots in place, and a plurality of sets of pile warps of different colors held in place by portions lying between the upper and lower weft shots, other portions of the pile warps being raised between adjacent upper weft shots in accordance with a pattern to provide loops forming a pile surface, the loops at the points of color change being higher than those elsewhere.

5. A pile fabric which comprises the combination of stuffer warps, weft shots lying above and below the stuffer warps, binder warps crossing the weft shots above and below and binding the weft shots in place, and a plurality of sets of pile warps held in place by portions lying between the upper and lower weft shots, other portions of the pile warps being raised between adjacent upper weft shots in accordance with a pattern to provide loops, the last loop in any longitudinal series of loops of a single pile warp yarn being higher than the other loops in said series.

6. A pile fabric which comprises the combination of stuffer warps, weft shots lying above and below the stuffer warps, binder warps crossing the weft shots above and below and binding the weft shots in place, and a plurality of sets of pile warps held in place by portions lying between the upper and lower weft shots, other portions of the pile warps being raised between adjacent upper weft shots in accordance with a pattern to provide loops lying in rows extending transversely of the fabric, each row containing a full complement of loops, and the last loop in any longitudinal series of loops of a single pile warp yarn being higher than the other loops in said series.

7. A pile fabric which comprises the combination of stuffer warps, weft shots lying above and below the stuffer warps, binder warps crossing the weft shots above and below and binding the weft shots in place, and a plurality of sets of pile warps, each pile warp yarn having portions lying between the upper and lower weft shots and other portions raised between adjacent upper wefts in accordance with a pattern to provide loops, the pile surface formed by the loops having areas formed by loops of pile warp yarns

of a single set, each area including loops along its margin last formed which are higher than the loops formed of the same yarns within the area.

5. 8. A method of making a pile carpet or mat having a backing and a plurality of sets of pile warps, which comprises forming the backing with the pile warps held therein by parts of said backing, raising the pile warps selectively from the backing in accordance with a pattern and lowering the raised warps about pile wires and restoring them to the backing to provide longitudinal rows of loops of a single height, increasing the height of the loops in each transverse row, and then reducing the height of only those loops in said row which are directly followed in their respective longitudinal rows by loops of the same pile warp.
9. A pile carpet or mat comprising a backing, and a plurality of sets of pile warps held within the backing in generally parallel rows, each set including a plurality of pile warps of contrasting appearance, said warps being raised selectively from the backing in accordance with a pattern to provide longitudinal rows of loops forming a pile surface, the last loop in any longitudinal series of loops of a single pile warp being higher than the other loops in said series.
10. A method of weaving a pile fabric including stuffer warps, binder warps, weft shots, and a plurality of sets of pile warps, which comprises manipulating the several warps to form successive sheds, inserting the weft shots in the sheds both above and below the stuffer and pile warps and in position to be bound in place by the binder warps, raising the pile warps between adjacent upper weft shots in accordance with a pattern and lowering the pile warps about pile wires to provide loops of a single height, and subsequently reducing the height of all loops except the last in each longitudinal series of loops made of the same pile warp.
11. A method of weaving a pile fabric including stuffer warps, binder warps, weft shots, and a plurality of sets of pile warps, which comprises manipulating the several warps to form successive sheds, inserting the weft shots in the sheds both above and below the stuffer and pile warps and in position to be bound in place by the binder warps, raising the pile warps between adjacent upper weft shots in accordance with a pattern and lowering the pile warps about pile wires to provide loops of a single height, increasing the height of the loops in each transverse row, and then reducing the height of selected loops.
12. A method of weaving a pile fabric including stuffer warps, binder warps, weft shots, and a plurality of sets of pile warps, which com-

prises manipulating the several warps to form successive sheds, inserting the weft shots in the sheds both above and below the stuffer and pile warps and in position to be bound in place by the binder warps, raising the pile warps between adjacent upper weft shots in accordance with a pattern and lowering the pile warps about pile wires to provide loops of a single height, increasing the height of the loops in each transverse row, and subsequently reducing the height of all loops within an area representing a pattern figure except the loops last produced in said area and lying along a margin thereof.

13. A method of weaving a pile fabric including stuffer warps, binder warps, weft shots, and a plurality of sets of pile warps, which comprises manipulating the several warps to form successive sheds, inserting the weft shots in the sheds both above and below the stuffer and pile warps and in position to be bound in place by the binder warps, raising the pile warps between adjacent upper weft shots in accordance with a pattern and lowering the pile warps about pile wires to provide loops of a single height, and subsequently reducing the height of all loops except the last formed consecutively of a single pile warp.

14. A method of weaving a pile fabric including stuffer warps, binder warps, weft shots, and a plurality of sets of pile warps, which comprises manipulating the several warps to form successive sheds, inserting the weft shots in the sheds both above and below the stuffer and pile warps and in position to be bound in place by the binder warps, raising the pile warps between adjacent upper weft shots in accordance with a pattern and lowering the pile warps about pile wires to provide loops of a single height, and subsequently reducing the height of all loops lying in a line lengthwise of the fabric except the loop immediately preceding a color change in said line.

15. A method of weaving a pile fabric including stuffer warps, binder warps, weft shots, and a plurality of sets of pile warps, which comprises manipulating the several warps to form successive sheds, inserting the weft shots in the sheds both above and below the stuffer and pile warps and in position to be bound in place by the binder warps, raising the pile warps between adjacent upper weft shots in accordance with a pattern and lowering the pile warps about pile wires to provide loops of a single height, increasing the height of loops in each transverse row, and withdrawing material from selected loops for use in the formation of subsequent loops.

HOWARD L. SHUTTLEWORTH.
